UNITED STATES PATENT OFFICE.

EDGAR A. BAUGHAN, OF ATLANTA, GEORGIA.

DESIGN FOR A BADGE.

Application filed August 28, 1924. Serial No. 10,570. Term of patent 14 years.

To all whom it may concern:

Be it known that I, EDGAR A. BAUGHAN, a citizen of the United States, residing at Atlanta, in the county of Fulton and State of Georgia, have invented a new, original, and ornamental Design for Badges, of which the following is a specification, reference being had to the accompanying drawings, forming part thereof.

The figure is a plan view of a badge, showing my new design.

I claim:

The ornamental design for a badge, as shown.

EDGAR A. BAUGHAN.
